ASH TRAY

William S. Pearson, Baltimore, Md.

Application October 23, 1958, Serial No. 53,103

Term of patent 14 years

(Cl. D85—2)

I claim:

The ornamental design for an ash tray, substantially as shown and described.
